UNITED STATES PATENT OFFICE.

FRANK HUMPHRIS, OF BOSCOMBE, BOURNEMOUTH, ENGLAND, ASSIGNOR OF ONE-HALF TO KENNETH ALEXANDER ROBERTS, OF LONDON, ENGLAND.

MECHANICAL PRESS.

Application filed October 24, 1921. Serial No. 509,994.

To all whom it may concern:

Be it known that I, FRANK HUMPHRIS, a subject of the King of Great Britain, residing at Boscombe, Bournemouth, Hampshire, England, have invented new and useful Improvements in Mechanical Presses, of which the following is a specification.

This invention relates to a mechanical press for the manufacture of horseshoes or other articles and provides a press that is simple to construct and capable of exercising great pressure and in which the movable pressure face travels in true parallel. Backlash and excessive wear are reduced to a minimum in the members which take the compression load by so constructing the apparatus that the sliding action on the bearing surfaces is very small while the bearing area is very large.

20 The improved press differs essentially as regards its design and construction from standard practice, as it does also in the selection and placement of the principal members or parts by and through which the pressure is exercised.

The invention is illustrated in the accompanying drawing, in which:

Figure 1 is a front elevation of one type of single ram power press of the type which uses edge-pressure-ram-plates with the pivots integral with the bars or plates connecting them.

Figure 2 is a perspective view on an enlarged scale of a solid edge-pressure-ram-plate or of an edge-pressure-slide-plate having its pivots integral with the bar or plate connecting them.

Figure 3 is a perspective view, with some of the parts shown in sections of an edge-pressure-ram plate not provided with pivots, but capped with hardened material on each bearing face and as an example of how its bearing acts, it is shown standing in a broken piece of the ram which ram has in its grooves liners of channel form, also this figure shows two broken sections of the locating and withdrawing plates in their correct position to accommodate the pivots of a plate of the kind shown in Figure 2.

50 Figure 4 is a part view, on a reduced scale, of the front elevation of the machine shown in Figure 1, with the locating and withdrawing plates removed to enable the

action of the machine to be more clearly understood.

Figure 5 is a side elevational view, on an enlarged scale, of a portion of an edge-pressure-ram-plate or the like part shown in cross-section with its wedge-wise cap thereon in its relative position shown in longitudinal section, together with its bearer-plate, ram, or like part containing a wear resisting liner with wedge-like face, both in longitudinal section and in their relative working position to the other parts thereon, and the set-screws in side elevation and in their co-operating relative clamping position for adjustment of the sliding wedge-formed parts.

Figure 6 is a front elevation on an enlarged scale, of the same parts as shown in Figure 5.

Figure 7 is a cross-sectional view, on an enlarged scale, of an edge-pressure-ram-plate, or the like part, with enlarged rounded-edges to increase the bearing area.

Figure 8 is a cross-sectional view, on an enlarged scale, of an edge-pressure-ram-plate or like part made up in laminar form from a number of sheets or strips of material or metal and containing as separate units in or on two or more of their edges (whether these are provided parallel, wedge-wise, or tapering), rounded capping or bearing faces with a reduced portion remote from said bearing-faces which is secured by rivets, screws, or welding.

Figure 9 is a front elevation, partly in section, of one type of double-ram power press showing the relative position of removable parts when the machine is fully open, the front locating and withdrawing plates being removed.

Like letters of reference refer to like parts throughout the drawings.

The novel features and essential parts, and around which the press-machine forming the subject of this invention is designed to function, are what are herein referred to as the edge-pressure-ram-plates *a* or such other mechanical equivalents therefor and their direct concomitants. The action of these edge-pressure-ram-plates *a*, which contain no joints to wear or become loose, are given a herring-bone or laminiform position of placement in the machine in relation one to the other, and when in op-

eration their action may be compared, on account of the great force obtained by their employment, to a large number of knee-joints or knee-levers, if such could be acting simultaneously side by side.

The fundamental principle of the press according to this invention is the provision of one or more pressure platens or rams *b*, two of which are caused to move towards each other in a double ram machine, and one pressure platen or ram is caused to move towards the bed or bolster *c* of the press in a single ram machine. This movement is accomplished by means of a number of edge-pressure-ram-plates *a*, or their equivalents. The rams or pressure platens *b* are constrained, when in operation, in the double ram machine to approach one another by means of the movement imparted to two or more sets of edge-pressure-ram-plates *a*, each set consisting of a minimum of two plates, one set of which, provided with rounded edges *a'*, Figure 2, *a²*, Figure 3, at one end engage in grooves *b'* Figure 3 in that face of the ram remote from the die carrying face thereof, and the opposite ends thereof are also provided with rounded edges *a'* or *a²* which engage with and are fulcrumed in grooves provided in a bearer-plate or plates *e*, Figure 1, suitably attached to the frame of the press *f*.

In any set of edge-pressure-ram-plates some of the ram plates may, as shown in Figure 2, be formed with pivots *a³* adapted to extend into holes *k'* in locating and withdrawing plates *k*, and some of the pressure ram plates may, as shown in Fig. 3, be formed without such pivots, the plates without pivots being conveniently interposed with those having such pivots. The plates *k* may be formed without holes *k'* adjacent the ends of grooves *b* which receive plates without pivots, or the plates *k* may be omitted or cut away adjacent the ends of the grooves *b* which receive plates without pivots. For example, the end ram plates of a set may be provided with pivots and the intermediate plates may be formed without such pivots. The plates with pivots, in addition to functioning as pressure plates, also serve as links to connect the rams and bearer plates.

The grooves *b'* in the pressure-platens or rams *b* and the grooves *c'* Figure 4, provided in the bearer plates *e* and also the grooves *g'* provided in the reciprocating bearer-plate *g* are each contained in or on a separate attachable part or unit piece *h*, Figure 6 (when the machine is employed for heavy service), which part or parts is or are in the form of wear-resisting anti-friction liners or blocks composed of hardened steel, bronze or other suitable material, said liners or blocks *h* being provided on their faces remote from those en-

gaging with the edge-pressure-ram-plate with wedge-wise faces *h'* and, when constrained by means of set-screws or their equivalent *h²*, are capable of moving longitudinally and in such a manner as to act in conjunction with wedge-wise and grooved faces provided on or in the pressure-platens or rams *b*, the bearer-plates *e*, the reciprocating bearer-plate *g*, or such other like part, and thus take up any wear or inequality of distance that may exist between the rounded faces of the edge-pressure-ram-plates *a* or the like part and also enable the distance apart of the bearing surfaces thereof in each case to be equalized or adjusted. Where no provision for adjustment is necessary, i. e., for like service no liners or blocks *h* will be employed, but for medium service renewable channel liners *h³* of hardened material as shown in Figure 3 will be used.

The rounded or bearing ends of the edge-pressure-ram-plates or like constructed parts *s* Figure 9, when required for heavy service, are provided with separate attachable parts or units (suitably affixed thereon in slides, or by screws or the like so that they can be easily renewed) either in the form of wear resisting wedge-wise caps *a⁴* Figure 6, or rounded or channelled bearing-ends *a²*, in each case made of hardened steel or other suitable material and, in the case of the wedge-wise caps *a⁴*, capable of longitudinal adjustment in a manner similar to that employed for the liners or blocks *h*.

The edge-pressure-ram-plates *a* or like constructed parts *s* may be made in one piece, or they may be capped with hardened material as beforementioned, but preferably they will be constructed in laminar form from two or a number of plates of metal *a⁵*, as shown in Figure 8, said plates being made with parallel or wedge-wise edges adjacent to their capped ends *a⁶* which are provided with reduced parts *a⁷* for attaching to the plates which are made to suit either a parallel or a wedgewise form of capping as required.

In the edge-pressure-ram-plates as shown in cross-section in Figure 7, the section may be described as of dumb-bell form; this being provided to give an increased bearing-area or sliding surface in contact, and is especially adaptable for high speed operation of the press. The section may be constructed in various ways and is given merely by way of example.

When the pressure platens or rams have approached each other to their nearest position or in other words, when the press is closed, the edge-pressure-ram-plates are vertical or at right angles to the bearer-plates and the pressure faces of the platens or rams. The operating means causing this beforementioned condition to occur in the

double ram machine are composed of edge-pressure-slide plates acting upon the face of one end of each pressure-platen or ram in a manner similar, but in this case at right angles to the edge-pressure-ram-plates. These edge-pressure-slide-plates *s* engage one end of each ram and one end of a slide *s'* which is slidably mounted in the frame of the press, said slide *s'* being attached to a beam *t* fulcrumed at one end by means of a bearing *t'* to the frame *f* of the machine and connected at the other end by means of a bearing *t''* to a connecting rod *r* or its equivalent, which in turn is connected to the crank *p'* of the machine, the crank-shaft *p* of which carries a flywheel *o*, and suitable clutch motion as ordinarily employed; or the closing and opening of the pressure-*platens* or rams *b* may be accomplished by means of any equivalent mechanical device. Locating and withdrawing plates *k* having the holes *k'* are provided for locating the pivots *a³* and the bearing faces *a'* or the like in the grooves *b', e', g'* or the like in the rams *b*, and the bearer plates *e* and *g* or the like, and serve in conjunction with the pivots *a³* of the edge pressure ram plates *a* or the like, as means for opening or withdrawing the ram faces from their closed position, the edge pressure ram plates with pivots *a³* serving as links for holding the pressure platens or rams *b* in their correct working positions. Said plates *k* are secured to the bearer plates *e*, *g* and the ram *b* or like parts by screws *k²* or the like.

Preferably the repetition operation of a double-ram machine briefly is as follows:— An article is placed between the faces of the pressure-*platens* or rams (*b*, *c*, Figure 1, or *b*, *b*, Figure 9), and then the motion controlling the rams is made operative, which in the case where a constantly revolving flywheel *o* is used, is done by causing the clutch to engage, and this in turn involves the crankshaft *p* and causes reciprocation of the connecting-rod *r*, which operates on the edge of the pressure platen or ram *b* either directly (Figure 1) or on the pressure platens or rams *b* (Figure 9) directly through the beam *t*, slide *s'* and slide plates *s*, (causing them in a vertical machine to move in a horizontal path) and these rams *b* are constrained to close by means of the edge-pressure-ram-plates *a* controlling them, and by so doing apply great force to material interposed between the pressure platens or ram faces; when this is done the pressure-*platens* or rams automatically return to their full open position and the operation can be immediately repeated at the will or convenience of the operator.

In the single-ram type of machine as shown in Figure 1 where the bottom die-member *n* is secured to the bed or bolster *c* of the press-frame *f*, provision is made

through said die-member *n* and the bed or bolster *c*, by providing a passage-way for outcuttings or the like produced by the dies when the press is in operation to fall through, and such passage-way opens out into cavity *d* in the frame *f*. In this machine when in operation, the ram or pressure-platen *b* is constrained to approach the bed or bolster *c* of the press by means of movement imparted to two or more sets of edge-pressure-ram-plates *a*, each set consisting of two or more plates *a*, and said plates *a* are all provided on their bearing-ends with rounded-edges *a'*, one set thereof each at their one end *a'* engage and are fulcrumed in grooves *b'* in that face of the ram *b* remote from the die-carrying-face thereof, and each at their other end *a'* engage with and are fulcrumed in grooves *g'* in a reciprocating bearer-plate *g*, which plate *g* in the single-ram press is interposed between two sets of edge-pressure-ram-plates *a*; the second set thereof, each at their one end *a'*, engage and are fulcrumed in grooves *g'* in the beforementioned reciprocating bearer-plate *g*, and each at their other end *a'* engage and are fulcrumed in grooves *e'* in a bearer plate *e*. When this press is in operation, the flywheel *o* causes the crankshaft *p* to revolve, which constrains the connecting rod *r* to impart movement to the reciprocating bearer-plate *g*, which in turn causes the edge-pressure-ram-plates to assume a vertical path or arrive at right angles, or approximately so, to the plane of the bed or bolster *c*, and in so doing these plates *a* cause the ram *b*, which is constrained by its side blocks *j* in the guides *i*, to approach the bed or bolster *c* of the press, and in so doing exercise pressure on whatever material may be placed between said ram *b* and bolster *c*.

By increasing or varying the throw of the crank *p'* so as to cause the edge-pressure-ram-plates *a* to pass the right-angle-line above referred to, in relation to the bed or bolster *c* of the press, two power strokes or pressure deliveries instead of one for each revolution of the crank *p'* will be the resultant condition obtained.

The same press can be made to have a continuous motion in which a regular reciprocating movement is given to the pressure-*platens* or rams, and when this is done, hot forging, hot stamping, thicknessing and other similar work can be accomplished, in addition to using the machine for ordinary press work.

By affixing suitable dies on the ram and the bolster parts of the machine, horse-shoes and a large variety of other articles can be easily hot-stamped, cold-pressed and die-finished in the same machine, which, by its adjusting devices can be set to give

either a slow continuing pressure, a blow, or an intermittent movement.

I claim:—

1. In a mechanical press, a ram, a bearer plate, edge pressure ram plates having rounded ends and of which the length substantially equals the width of the ram and bearer plate, said ram and bearer plate having correspondingly rounded seats for the respective ends of the edge pressure ram plates extending from side to side of the said ram and bearer plate, withdrawing plates on the ram and bearer plate, and trunnions extending from the said edge pressure ram plates into bearings provided therefor in the said withdrawing plates.
2. In a mechanical press, a ram, a bearer plate, edge pressure ram plates between the said ram and bearer plate, wear resisting caps on the pressure edges of the said edge pressure ram plates, and wear resisting liners arranged to form seats for the pressure edges of the edge pressure ram plates in the ram and bearer plate respectively.
3. In a mechanical press, a ram, a bearer plate, edge pressure ram plates between the said ram and bearer plate, wear resisting caps on the pressure edges of the said edge pressure ram plates, means for detachably securing the said caps to the said plates, and seats for the said caps in the ram and bearer plate respectively.
4. In a mechanical press, a ram, a bearer plate, edge pressure ram plates between the said ram and bearer plate, wear resisting liners arranged to form seats for the pressure edges of the edge pressure ram plates in the ram and in the bearer plate, and means for detachably securing the said liners to the ram and bearer plate respectively.
5. In a mechanical press, a ram, a bearer plate, edge pressure ram plates extending from side to side of the ram and bearer plate, tapered wear-resisting caps, the edges of the edge pressure ram plates being inclined to the sides thereof to serve as slide faces for accommodating said tapered wear-resisting caps, and tapered wear-resisting liners, the ram and bearer plate having grooves inclined to the plane faces thereof to serve as slide faces for accommodating said tapered wear-resisting liners.
6. In a mechanical press, a ram, a bearer plate, edge pressure ram plates extending from side to side of the ram and bearer

plate, wear-resisting caps tapered wedge-wise and serving as pressure edges of the edge pressure ram plates and wear resisting liners tapered wedge-wise and serving as seats in which the pressure edges of the edge pressure ram plates in the ram and bearer plate move respectively.

7. In a mechanical press, a ram, a bearer plate, edge pressure ram plates extending from side to side of the ram and bearer plate, wear resisting caps tapered wedge-wise and serving as pressure edges of the edge pressure ram plates, and wear-resisting liners tapered wedge-wise and serving as seats in which the pressure edges of the edge pressure ram plates in the ram and bearer plate move respectively, and means for separately longitudinally adjusting the tapered caps and liners.

8. In a mechanical press, the combination of a movable ram guided to move parallel to itself between its extreme open and closed positions, a bearer plate, a plurality of edge pressure ram plates extending from side to side of the said ram and bearer plate, said edge pressure ram plates having rounded pressure edges, correspondingly rounded seats in the said ram and bearer plate for the respective rounded pressure edges of the edge pressure ram plates, withdrawing plates, trunnioned edge pressure ram plates, and a reciprocatory slide operating in a direction substantially at right angles to the direction of movement of the ram to and from its open and closed positions, said slide operating in conjunction with said withdrawing plates and trunnioned edge pressure ram plates to effect movement of the ram and bearer plate.

9. In a mechanical press, a ram, a bearer plate, edge pressure ram plates having trunnions, withdrawing plates having bearings to receive said trunnions, and other edge pressure ram plates without trunnions.

10. In a mechanical press, a ram, a bearer plate, edge pressure ram plates extending between the said ram and bearer plate, the said edge pressure ram plates comprising a plurality of plates secured together and carrying rounded end caps, and seats in the ram and bearer plate for the said end caps.
